RECOIL-OPERATED SELF-LOADING FIREARM

Carl G. Swebilius, Hamden, Conn., assignor to
 Western Cartridge Company, New Haven,
 Conn., a corporation of Delaware

Application July 30, 1940, Serial No. 348,511

8 Claims. (Cl. 42—4)

This invention relates to improvements in firearms and more particularly to firearms of the so-called "self-loading" or "automatic" type wherein the barrel of the firearm reciprocates axially upon the discharge of the firearm actuating the mechanism to effect the ejection of a just-fired cartridge and the subsequent insertion of a fresh cartridge into the cartridge chamber of the firearm.

One object of the present invention is to provide a self-loading firearm of the reciprocating-barrel type having a superior construction and arrangement of parts whereby a relatively-short axial movement of the barrel-unit imparts a relatively-long axial movement to the breech-bolt of the firearm.

Another of the objects of the present invention is to provide a superior recoil-operated self-loading firearm which may be relied upon to function properly over long periods of use and which may be produced at a relatively-low cost for manufacture.

A further object of the present invention is to provide an automatic firearm of the type referred to, having a superior construction and arrangement of parts whereby a durable, compact and rugged construction combined with simplicity of manufacture is achieved.

Still another object of the present invention is to provide a superior automatic firearm of the reciprocating-barrel type wherein the actuation of the mechanism is accomplished with a minimum amount of recoil shock.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken view in side elevation of a recoil-operated self-loading firearm embodying the present invention;

Fig. 2 is a view partly in vertical central-longitudinal section and partly in side elevation of the central portion of the firearm, the breech-bolt being shown in its breech-closing position and the barrel-unit in its full forward position;

Fig. 3 is a horizontal sectional view taken on the line 3—3 of Fig. 2;

Fig. 4 is a view similar to Fig. 2 but showing the barrel-unit in its fully recoiled or retired position;

Fig. 5 is a view similar to Fig. 4 but showing the breech-bolt in its fully retired position and the barrel-unit in its full forward position;

Fig. 6 is a transverse sectional view taken on the line 6—6 of Fig. 2;

Fig. 7 is a similar view taken on the line 7—7 of Fig. 2;

Fig. 8 is a transverse sectional view taken on the line 8—8 of Fig. 2;

Fig. 9 is a broken view in side elevation of the rear portion of the reciprocating-barrel together with the forward portion of the barrel-extension forming a unit therewith;

Fig. 10 is an underside view thereof;

Fig. 11 is a transverse sectional view taken on the line 11—11 of Fig. 9;

Fig. 12 is a perspective view of the transmitting-lever;

Fig. 13 is a side-elevational view of the breech-bolt;

Fig. 14 is a perspective view of the bolt-operating bar; and

Fig. 15 is a perspective view of the transmitting-plunger.

25 The particular recoil-operated self-loading firearm herein chosen for illustrating the present invention includes a receiver 20 having a mechanism-receiving chamber 21 in its interior which communicates with the exterior of the right-hand side-face of the said receiver by means of an ejection-opening 22 as shown in Fig. 1. Rigid with and extending rearwardly from the receiver 20 is a receiver-extension 23 serving to firmly attach a buttstock 24 to the said receiver. Depending from the underside of the receiver 20 is a loop-like trigger-guard 25 into which projects a trigger 26 adapted to effect the discharge of the firearm in any approved manner not requiring detailed description herein.

40 Extending forwardly from the forward end of the receiver 20 is a reciprocating barrel-unit 27 which includes a barrel 28 and a cylindrically-contoured barrel-extension 29 threadedly secured to the rear end of the said barrel so as to form 45 a rigid feature thereof. The barrel-extension 29 projects rearwardly from the barrel 28 into the upper portion of the mechanism-receiving chamber 21 of the receiver 20 with capacity for axial reciprocation in the said mechanism-receiving chamber 21 in the general manner of recoil-operated automatic or self-loading firearms.

The barrel-extension 29 of the barrel-unit 27 has a top-wall 30 which is transversely curved exteriorly and a side-wall 31 extending downwardly from the said top-wall 30 at the left-

hand side thereof and similarly transversely curved exteriorly in continuation of the curvature of the said top-wall. The top-wall 30 and the side wall 31 of the barrel-extension 29 thus provide a bolt-receiving chamber 32 opening downwardly and also outwardly through the right-hand side-face of the said barrel-extension in registration with the ejection-opening 22 in the receiver 20 when the barrel-unit 27 is in its full forward position. The said bolt-receiving chamber 32 is adapted to receive a breech-bolt 33 which is movable both with and relative to the said barrel-unit 27. The breech-bolt 33 is releasably locked in its breech-closing position in the bolt-receiving chamber 32 as shown in Fig. 2 in a manner as will hereinafter appear.

The barrel-extension 29 of the barrel-unit 27 has an external diameter larger than the external diameter of the abutting rear-portion of the barrel 28 so as to provide an annular forwardly-facing stop-shoulder 34 normally engaged with the rear face of the body-portion 35a of a barrel-guiding member 35. The said barrel-guiding member 35 is provided in the upper part of its body-portion 35a with a barrel-receiving passage 36 through which the barrel 28 forwardly extends. Forwardly projecting from each of the opposite sides of the body-portion 35a of the barrel-guiding member 35 are two parallel laterally-spaced-apart barrel-guiding arms 37 and 38, each of which is formed in its inner face with a guide-groove 39 extending in parallelism with the longitudinal axis of the barrel-unit 27. Reciprocating in the guide-grooves 39—39 respectively are guide-ribs 40—40, one of which is formed integrally on each of the respective opposite sides of an actuating-lug 41 rigid with and depending from the barrel 28 at a point forwardly of the rear end thereof as is clearly shown in Figs. 9, 10 and 11. The said actuating-lug may be formed integral with the barrel 28 or welded, brazed or otherwise secured thereto.

The barrel 28 is formed on each of the respective opposite sides thereof with one of a complementary pair of lugs 42—42 located above the actuating-lug 41 and each is provided with a longitudinal aperture receiving with a free sliding fit the forward portion of one of a complementary pair of spring-guide rods 43—43. One of the said pair of rods 43—43 is thus located on each of the respective opposite sides of the barrel 28 adjacent the rear portion thereof. Immediately adjacent its rear end, each of the spring-guide rods 43—43 is formed with an integral annular collar 44 and with a locating-stud 45 extending rearwardly therefrom. The locating-stud 45 of each of the spring-guide rods 43—43 is seated in a suitable forwardly-opening locating-pocket, one of which is formed on each of the respective opposite sides of the barrel-receiving passage 36 in the body-portion 35a of the barrel-guiding member 35 immediately above the upper surface of the respective barrel-guiding arms 37 and 38.

Each of the spring-guide rods 43—43 is respectively encircled by one of two helical barrel-return springs 46—46 each of which bears at its rear end against the forward face of the collar 44 of the particular spring-guide rod 43 which it encircles. Each spring 46 thus thrusts rearwardly against the forward face of the body-portion 35a of the barrel-guiding member 35. The forward end of each of the barrel-return springs 46—46 thrusts forwardly against the rear

face of the adjacent one of the lugs 42—42 of the barrel 28, as is particularly well shown in Figs. 2, 3 and 4. In this manner the barrel-return springs 46—46 exert a constant effort to maintain the barrel-unit 27 in its forward position in which the stop-shoulder 34 thereof constituted by the front end of the barrel-extension 29 is in engagement with the rear face of the body-portion 35a of the barrel-guiding member 35, as clearly shown in Figs. 2 and 5.

The barrel-guiding arms 37 and 38 of the barrel-guiding member 35 have secured thereto by screws 47, a fore-stock 48 which is of substantially U-shaped form in cross-section to accommodate the lower portion of the barrel 28, the said barrel-guiding arms 37 and 38, and also to accommodate a tubular-magazine 49 located below the barrel 28 in vertical spaced relationship thereto and extending in substantial parallelism therewith. The said tubular-magazine 49 is provided adjacent its rear end with an annular flange or collar 50, the rear face of which presses against the forward face of the lower part of the body-portion 35a of the barrel-guiding member 35 around a magazine-receiving passage 51 therein. The portion of the tubular-magazine 49 to the rear of its collar 50 is provided with external interrupted threads which interengage with interrupted threads formed within the lower forward portion of the receiver 20. In this manner the tubular-magazine 49 serves to hold the barrel-guiding member 35 to the receiver 20, so that the said barrel-guiding member under normal conditions constitutes a rigid extension of the said receiver.

Adjacent the forward end of the barrel-guiding arm 37 of the barrel-guiding member 35, the said barrel-guiding arm is formed with a transversely-extending clearance-slot 52 intersecting the adjacent one of the guide-grooves 39 and into which extends the adjacent fixed-end 53 of a pivotal plate-like transmitting-lever 54. The transmitting-lever 54 is mounted for pivotal movement on a vertically-extending pivot-pin 55 supported in the adjacent portions of the barrel-guiding arm 37 as is clearly shown in Fig. 7. The said transmitting-lever extends transversely across the space between the barrel-guiding arms 37 and 38 to the rear of and adjacent to the actuating-lug 41 of the barrel 28, as is particularly well shown in Fig. 3. The transmitting-lever 54 is formed with an arcuate forward edge constituting a cam-surface 56 adapted to be engaged by a complementary cam-surface 57 forming part of the rear face of the actuating-lug 41 of the barrel 28. At its outer or free-end, the transmitting-lever 54 is formed with a nose 58 having its rear face outwardly curved and extended into a transverse clearance-slot 59 formed in the adjacent forward portion of the barrel-guiding arm 38 and intersecting the guide-groove 39 therein.

The nose 58 of the transmitting-lever 54 is positioned in the clearance-slot 59 just above referred to and is adapted to engage the forward end of a cylindrical transmitting-plunger 60 freely mounted for axial reciprocation in a guide-passage 61 extending longitudinally in the barrel-guiding arm 38 with its forward portion intersecting the clearance-slot 59 of the said arm 38, as is clearly shown in Figs. 3 and 7. The guide-passage 61 just referred to opens outwardly through the rear face of the body-portion 35a of the barrel-guiding member 35 in axial alignment with a clearance-passage 62 formed in the for-

ward wall of the receiver 20 and which, in turn, opens rearwardly into the forward portion of the mechanism-receiving chamber 21 of the said receiver.

The transmitting-plunger 60 above referred to is mounted in the guide-passage 61 for free sliding movement therein and is retained in place against axial displacement therefrom by a vertically-extending retaining-pin 63 mounted in the adjacent portions of the barrel-guiding arm 38 intersecting and laterally projecting into the guide-passage 61. The retaining-pin 63 as thus located is in position to be engaged by the front or rear walls respectively constituting stop-abutments 64 and 65 of a longitudinal clearance-notch 66 formed on the outer periphery of the transmitting-plunger 60.

Extending axially through the clearance-passage 62 and into the rear portion of the guide-passage 61 and normally located therein, is the forward portion of a bolt-operating bar 67, the forward end of which is normally positioned adjacent the rear end of the transmitting-plunger 60 for engagement thereby, in a manner as will hereinafter appear. The said bolt-operating bar 67, as is particularly well shown in Figs. 3 and 6, reciprocates in and is guided by a longitudinal guide-groove 68 formed in the inner face of the left-hand side-wall of the receiver 20 axially in line with the clearance-passage 62 in the forward wall thereof. Intermediate its opposite ends the bolt-operating bar 67 is provided with an inwardly-projecting guide-lug 69 reciprocating in a longitudinal guide-groove 70 formed in the forward portion of the left-hand side-face of the breech-bolt 33. Adjacent its rear end the bolt-operating bar 67 is formed with a transverse-passage 71 receiving the adjacent end of a bolt-operating pin 72 extending transversely of the firearm through a pair of corresponding arcuate cam-slots 73—73 one of which is respectively formed in each of the side-walls of a longitudinally-extending downwardly-opening clearance-groove 74 formed in the underside of the breech-bolt 33 and across which the said bolt-operating pin extends.

Mounted on the right-hand side-face of the breech-bolt 33 is a manual bolt-operating slide 75 provided at its forward end with an outwardly-projecting finger-piece 76 and formed adjacent its rear end with a transverse passage 77 receiving the adjacent end of the bolt-operating pin 72 just above referred to. Adjacent its forward end the operating-slide 75 is provided on its inner face with an inwardly-projecting guide-lug 78 reciprocating in a guide-groove 79 formed in the forward portion of the right-hand side-face of the breech-bolt 33. By means of the slide 75 the breech-bolt 33 may be manually moved rearwardly in a manner as will hereinafter appear.

The breech-bolt 33 is releasably locked in its breech-closing position in the bolt-receiving chamber 32 of the barrel-extension 29 as is shown in Fig. 2, by an integral upwardly-projecting longitudinal locking-rib 80. The rear end of the locking-rib 80 constitutes an abutment 81 adapted to engage a forwardly-facing bolt-locking abutment 82 forming the rear wall of a longitudinal clearance-slot 83 provided in the top-wall 30 of the barrel-extension 29.

Each of the cam-slots 73—73, before referred to, of the breech-bolt 33 is formed with an arcuate lower rear wall constituting one of two unlocking-cams 84—84 and with substantially-L-shaped locking-cams 85—85 forming the upper forward walls of the said cam-slots 73—73.

Each of the unlocking-cams 84—84 coacts with the adjacent portions of the bolt-operating pin 72 located in the respective cam-slots 73—73 to rock the rear portion of the breech-bolt 33 downwardly to thus retire the locking-rib 80 thereof out from the clearance-slot 83 in the barrel-extension 29 for purposes as will hereinafter appear.

The locking-cams 85—85 of the breech-bolt 33 are also adapted to coact with the bolt-operating pin 72 to raise the rear portion of the breech-bolt 33 when the same is in its breech-closing position and enter the locking-rib 80 thereof into the clearance-slot 83 of the barrel-extension 29 to lock the said breech-bolt in its breech-closing position in a manner as will hereinafter appear.

Pivottally organized with the central portion of the bolt-operating pin 72 and located in the clearance-groove 74 in the breech-bolt 33 is the forward portion of a bolt-closing link 86. The rear end of the said link is pivotally secured to the forward end of a spring-plunger 87 mounted in the tubular receiver-extension 23 of the receiver 20 with capacity for reciprocating movement therein and having an axial rearwardly-opening spring-receiving pocket 88. The spring-receiving pocket 88 of the spring-plunger 87 receives the forward portion of a helical bolt-return spring 89 mainly housed in the receiver-extension 23 as is shown particularly well in Fig. 1.

The bolt-return spring 89 serves, through the intermediary of the spring-plunger 87, bolt-closing link 86 and the bolt-operating pin 72 acting upon the locking-cams 85—85 of the breech-bolt 33, to constantly but yieldingly urge the said breech-bolt forwardly and upwardly into its locked breech-closing position within the bolt-receiving chamber 32 of the barrel-unit 21.

For the purposes of description let it be assumed that the breech-bolt is locked in its breech-closing position and that the cartridge-chamber 28 of the barrel 28 contains a cartridge and the various parts are in the positions shown particularly well in Figs. 2 and 3. Under these conditions the firearm may be discharged.

Immediately following the discharge of the firearm, the barrel-unit 21, comprising the barrel 28 and the barrel-extension 29, together with the breech-bolt 33, will be moved rearwardly by the recoil forces generated by the discharge of the just-fired cartridge. The barrel-unit 21 will be moved rearwardly against the tension of the barrel-return springs 46—46 while the breech-bolt 33 will be retarded against the tension of the bolt-return spring 89. The barrel-unit 21 together with the breech-bolt 33 will thus have been moved rearwardly a relatively-short distance from the positions they occupy in Fig. 2 to the positions in which they are shown in Fig. 4. The rearward travel of the barrel-unit 21 is halted as shown in Fig. 4 by the engagement of the rear end of the barrel-extension 29 with a forwardly-facing stop-abutment 90 provided in the rear portion of the mechanism-receiving chamber 21 of the receiver 20, as is particularly well shown in Figs. 2, 3, 4 and 5.

The rearward travel of the barrel-unit 21 will correspondingly move the actuating-lug 41 of the barrel 28 and cause the cam-surface 57 of the said lug to engage the cam-surface 56 of the transmitting-lever 54. This engagement will swing the transmitting-lever 54 rearwardly about its pivot-pin 55 from the position in which it is shown in full lines in Fig. 3 to substantially the dotted line position indicated in the same figure.

75 This rearward swinging movement of the trans-

mitting-lever 54 will cause the nose 58 thereof to sharply strike the forward end of the transmitting-plunger 60 to "kick," so to speak, the said plunger rearwardly against the forward end of the bolt-operating bar 67 concurrently moving the latter rearwardly.

In imparting rearward movement to the transmitting-plunger 60, the transmitting-lever 54 acts as an accelerator. This action will be apparent when it is observed that as the actuating-lug 41 of the barrel-unit 27 initially moves the said transmitting-lever 54, the nose 58 of the latter is located well forwardly of the pivot-pin 55 so that, relatively speaking, the cam-surface 57 of the actuating-lug 41 applies its force initially at a point relatively remote from the said pivot-pin 55. As the action of the actuating-lug 41 in swinging the transmitting-lever 54 continues, the point of application of force to the said transmitting-lever will approach relatively nearer the pivot-pin 55 as is evident by comparing the full line position of the actuating-lug 41 and transmitting-lever 54 in Fig. 3 with the position of the same indicated by broken lines in the said figure.

The above-described action initiates the rearward travel of the transmitting-plunger 60 at a relatively-slow rate which is but slightly greater than a one-to-one ratio as compared with the movement of the said actuating-lug. As the described movement progresses, however, the ratio of movement between the actuating-lug 41 of the barrel-unit and the transmitting-plunger 60 ultimately reaches a point where the said transmitting-plunger is moved at substantially twice the speed of the said actuating-lug 41. After the actuating-lug 41 of the barrel-unit 27 and the transmitting-lever 54 have reached the limit of their rearward movement, the transmitting-plunger 60 and the parts propelled thereby will continue rearwardly in a manner and for the purposes as will hereinafter appear, the rearward travel of the said transmitting-plunger being halted by the engagement of its stop-abutment 64 with the retaining-pin 63.

The initial rearward movement of the transmitting-plunger 60, as above described, and the consequent rearward movement of the bolt-operating bar 67 will serve to rearwardly shift the bolt-operating pin 72 (and incidentally also the bolt-operating slide 75) relative to the breech-bolt 33. The described rearward movement of the bolt-operating pin 72 and the associated parts will be against the tension of the bolt-return spring 89 acting through the bolt-closing link 86 and the spring-plunger 87.

The rearward movement of the bolt-operating pin 72 and the associated parts, as above described, will cause the said bolt-operating pin to engage the adjacent unlocking-cams 84—84 of the cam-slots 73—73 in the breech-bolt 33 and thus force the rear end of the said breech-bolt downwardly to withdraw the abutment 81 thereof from its locking engagement with the bolt-locking abutment 82 of the barrel-extension 29. This unlocking action of the breech-bolt 33 will occur immediately following the stoppage of the rearward travel of the barrel-unit 27 by the engagement of the barrel-extension 20 with the stop-abutment 90 within the receiver 20, as shown in Fig. 4.

After having been unlocked as above described, the breech-bolt 33 will continue its rearward travel from the position shown in Fig. 4 into its full breech-opening position as shown in Fig. 70

5. While the breech-bolt 33 is traveling rearwardly from the position shown in Fig. 4 to the position shown in Fig. 5, the barrel-unit 27 will coincidentally be moving forwardly under the urge of the barrel-return springs 46—46 to again occupy the position in which it is shown in Fig. 5 relative to the breech-bolt 33.

When the parts have reached the positions in which they are shown in Fig. 5, the ejection of the just-fired cartridge through the ejection-opening 22 in the receiver 20 will have been completed and the firearm will be cocked.

The next movement in the sequence of operations which will occur, will be the return of the breech-bolt 33 under the urge of the bolt-return spring 89, into its full breech-closing and locked position as shown in Fig. 2. The forward travel of the breech-bolt, as just described, will effect the insertion of a fresh cartridge into the cartridge chamber of the barrel 28 of the barrel-unit 27 preparatory to the firearm again being discharged.

The described return movement of the breech-bolt 33 will be effected through the intermediary of the bolt-closing link 86, spring-plunger 87 and bolt-operating pin 72 to cause the latter to engage with the complementary locking-cams 85—85 of the breech-bolt 33 and force the rear end of the said breech-bolt upwardly to engage its abutment 81 with the bolt-locking abutment 82 of the barrel-extension 29.

Should it be desired to manually retire the breech-bolt 33 into its full breech-opening position for the purpose of removing a shell from the cartridge chamber of the barrel, or for the purpose of inserting a fresh cartridge thereinto, this may be accomplished by drawing rearwardly upon the finger-piece 76 of the bolt-operating slide 75 to thus cause the bolt-operating pin 72 to move rearwardly. This rearward movement of the bolt-operating pin 72 will cause the same to engage with the unlocking-cams 84—84 of the breech-bolt 33 with the effect of rocking the rear end of the said breech-bolt downwardly so as to first unlock the same and subsequently move the said breech-bolt rearwardly to its full breech-opening position as shown in Fig. 5.

By locating the transmitting-lever 54 or its equivalent forwardly of the breech-bolt 33 and vertically intermediate the barrel 28 and the tubular-magazine 49, it is possible to maintain the bulk of the receiver 20 at a minimum without unduly increasing the dimensions of the parts of the firearm forward of the said receiver. Furthermore, by the construction and arrangement exemplified in the accompanying drawings, an accelerating action upon the breech-bolt 33 is effected without undue complication of parts and without sacrifice of strength.

60 The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A recoil-operated self-loading firearm including in combination: a receiver-unit; a barrel-unit projecting forwardly from the said receiver-unit and movable with respect thereto under the forces developed by the discharge of a cartridge; a tubular-magazine also extending

forwardly from the said receiver-unit and in substantial parallelism with and beneath the said barrel-unit; a breech-bolt within the said receiver-unit and movable with respect to the same and with respect to the said barrel-unit; and bolt-actuating means constructed and arranged to transmit the recoil movement of the said barrel-unit to the said breech-bolt to effect the movement thereof relative to the said receiver-unit and the said barrel-unit, the said bolt-actuating means including a transmitting-lever located vertically intermediate the said barrel-unit and the said tubular-magazine and pivoted to the said receiver-unit at a point forwardly of the forward end of the said breech-bolt, a portion of the said transmitting-lever being positioned to be engaged by the said barrel-unit when the same recoils upon the discharge of a cartridge.

2. A recoil-operated self-loading firearm including in combination: a receiver-unit; a barrel-unit projecting forwardly from the said receiver-unit and movable with respect thereto under the forces developed by the discharge of a cartridge; a tubular-magazine also extending forwardly from the said receiver-unit and in substantial parallelism with and beneath the said barrel-unit; a breech-bolt within the said receiver-unit and movable with respect to the same and with respect to the said barrel-unit; and bolt-actuating means constructed and arranged to transmit the recoil movement of the said barrel-unit to the said breech-bolt to effect the movement thereof relative to the said receiver-unit and the said barrel-unit, the said bolt-actuating means including a transmitting-lever extending substantially horizontally between the said barrel-unit and the said tubular-magazine and pivoted to the said receiver-unit about a substantially-vertical axis, the said transmitting-lever being located at a point forwardly of the front end of the said breech-bolt, a portion of the said transmitting-lever being positioned to be engaged by the recoil of the said barrel-unit.

3. A recoil-operated self-loading firearm including in combination: a receiver-unit comprising a receiver and a receiver-extension projecting forwardly therefrom; a barrel-unit movable with respect to the said receiver-unit under the forces developed by the discharge of a cartridge, the said barrel-unit comprising a barrel projecting forwardly from the receiver of the said receiver-unit and a barrel-extension projecting rearwardly into and reciprocable in the receiver of the said receiver-unit; a tubular-magazine extending forwardly from the said receiver-unit and in substantial parallelism with and beneath the said barrel-unit; a breech-bolt within the receiver of the said receiver-unit and cooperating with the barrel-extension of the said barrel-unit, the said breech-bolt being movable with respect to both the receiver of the said receiver-unit and the barrel-extension of the said barrel-unit; and bolt-actuating means constructed and arranged to transmit the recoil movement of the said barrel-unit to the said breech-bolt to effect the movement of the latter, the said bolt-actuating means including a transmitting-lever located vertically intermediate the said barrel-unit and the said tubular-magazine and pivoted to the said receiver-extension at a point forwardly of the front end of the said breech-bolt and forwardly of the barrel-extension of the said barrel-unit, a portion of the said transmitting-lever being positioned to be engaged by the said barrel-unit

when the same recoils upon the discharge of a cartridge.

4. A recoil-operated self-loading firearm including in combination: a receiver-unit comprising a receiver and a receiver-extension projecting forwardly therefrom; a barrel-unit movable with respect to the said receiver-unit under the forces developed by the discharge of a cartridge, the said barrel-unit comprising a barrel projecting forwardly from the receiver of the said receiver-unit and a barrel-extension projecting rearwardly into and reciprocable in the receiver of the said receiver-unit; a tubular-magazine extending forwardly from the said receiver-unit and in substantial parallelism with and beneath the said barrel-unit; a breech-bolt within the receiver of the said receiver-unit and cooperating with the barrel-extension of the said barrel-unit, the said breech-bolt being movable with respect to both the receiver of the said receiver-unit and the barrel-extension of the said barrel-unit; and bolt-actuating means constructed and arranged to transmit the recoil movement of the said barrel-unit to the said breech-bolt to effect the movement of the latter, the said bolt-actuating means including a transmitting-lever extending substantially horizontally between the barrel of the said barrel-unit and the said tubular-magazine and pivoted to the said receiver-extension about a substantially-vertical axis, the said transmitting-lever being located at a point forwardly of the front end of the said breech-bolt and of the barrel-extension of the said barrel-unit, a portion of the said transmitting-lever being positioned to be engaged by the recoil of the said barrel-unit.

5. A recoil-operated self-loading firearm including in combination: a receiver-unit; a barrel-unit projecting forwardly from the said receiver-unit and movable with respect thereto under the forces developed by the discharge of a cartridge; a barrel-guiding member having guiding engagement with the said barrel-unit and extending forwardly from the said receiver-unit in substantial parallelism with and beneath the said barrel-unit, the said barrel-guiding member including two laterally-spaced-apart arms; a tubular-magazine also extending forwardly from the said receiver-unit in substantial parallelism with and beneath the said barrel-unit, the said tubular-magazine extending between the laterally-spaced-apart arms of the said barrel-guiding member; a breech-bolt within the said receiver-unit and movable with respect to the same and with respect to the said barrel-unit; and bolt-actuating means constructed and arranged to transmit the recoil movement of the said barrel-unit to the said breech-bolt, the said bolt-actuating means including a pivotal transmitting-lever located vertically intermediate the said barrel-unit and the said tubular-magazine and extending intermediate the two laterally-spaced-apart arms of the said barrel-guiding member, a portion of the said transmitting-lever being positioned to be engaged and pivotally moved by the said barrel-unit when the same recoils upon the discharge of a cartridge.

6. A recoil-operated self-loading firearm including in combination: a receiver-unit; a barrel-unit projecting forwardly from the said receiver-unit and movable with respect thereto under the forces developed by the discharge of a cartridge; a barrel-guiding member having guiding engagement with the said barrel-unit and extending forwardly from the said receiver-unit in substan-

tial parallelism with and beneath the said barrel-unit, the said barrel-guiding member including two laterally-spaced-apart arms; a tubular-magazine also extending forwardly from the said receiver-unit in substantial parallelism with and beneath the said barrel-unit, the said tubular-magazine extending between the laterally-spaced-apart arms of the said barrel-guiding member; a breech-bolt within the said receiver-unit and movable with respect to the same and with respect to the said barrel-unit; and bolt-actuating means constructed and arranged to transmit the recoil movement of the said barrel-unit to the said breech-bolt, the said bolt-actuating means including a transmitting-lever pivotally connected to one of the laterally-spaced-apart arms of the said barrel-guiding member and extending laterally across the space therebetween toward the other of said arms, a portion of the said transmitting-lever being positioned to be engaged and actuated by the said barrel-unit, and a reciprocating transmitting-member guided in the arm of the said barrel-guiding member opposite from the arm to which the said transmitting-lever is pivoted, the said reciprocating transmitting-lever being operatively connected to the said breech-bolt.

7. A recoil-operated self-loading firearm including in combination: a receiver-unit comprising a receiver and a buttstock extending rearwardly therefrom; a barrel-unit movable with respect to the said receiver-unit under the forces developed by the discharge of a cartridge, the said barrel-unit comprising a barrel-extension projecting rearwardly into and reciprocable in the receiver of the said receiver-unit and a barrel projecting forwardly from the said barrel-extension and provided forwardly of the latter with a depending actuating-lug; a barrel-guiding member having guiding engagement with the barrel of the said barrel-unit and extending forwardly from the said receiver-unit in substantial parallelism with and beneath the barrel of the said barrel-unit, the said barrel-guiding member including two laterally-spaced-apart arms receiving between them the depending actuating-lug of the barrel of the said barrel-unit; a breech-bolt within the said receiver-unit and operatively associated with the barrel-extension of the said barrel-unit for movement relative thereto; and bolt-actuating means constructed and arranged to transmit the recoil movement of the said barrel-unit to the said breech-bolt, the said bolt-

actuating means including a transmitting-lever located adjacent the actuating-lug of the barrel of the said barrel-unit for actuation thereby and pivotally connected to one of the laterally-spaced-apart arms of the said barrel-guiding member, the said transmitting-lever extending laterally across the space between the arms of the said barrel-guiding member in position to be engaged by the depending actuating-lugs of the barrel of the said barrel-unit.

8. A recoil-operated self-loading firearm including in combination: a receiver-unit comprising a receiver and a buttstock extending rearwardly therefrom; a barrel-unit movable with respect to the said receiver-unit under the forces developed by the discharge of a cartridge, the said barrel-unit comprising a barrel-extension projecting rearwardly into and reciprocable in the receiver of the said receiver-unit and a barrel projecting forwardly from the said barrel-extension and provided forwardly of the latter with a depending actuating-lug; a barrel-guiding member having guiding engagement with the barrel of the said barrel-unit and extending forwardly from the said receiver-unit in substantial parallelism with and beneath the barrel of the said barrel-unit, the said barrel-guiding member including two laterally-spaced-apart arms receiving the depending actuating-lug of the barrel of the said barrel-unit between them; a breech-bolt within the said receiver-unit and operatively associated with the barrel-extension of the said barrel-unit for movement relative thereto; and bolt-actuating means constructed and arranged to transmit the recoil movement of the said barrel-unit to the said breech-bolt, the said bolt-actuating means including a transmitting-lever located adjacent the actuating-lug of the barrel of the said barrel-unit and pivotally connected to one of the laterally-spaced-apart arms of the said barrel-guiding member, the said transmitting-lever extending laterally across the space between the arms of the said barrel-guiding member in position to be engaged by the depending actuating-lug of the barrel of the said barrel-unit, and a reciprocating transmitting-member guided in the arm of the said barrel-guiding member opposite from the arm to which the said transmitting-lever is pivoted, the said reciprocating transmitting-member being operatively connected to the said breech-bolt.
